UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,596, dated August 28, 1894.

Application filed July 31, 1894, Serial No. 819,102. Term of patent 8½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of vertically arranged stripes formed of spiral or twisted 10 ribbons, with small medallion figures filled with roses and leaves and attached to said stripes at regular distances apart by ribbon bows as represented in the accompanying drawing. Small bunches of roses and leaves 15 are also arranged on said stripes between the medallion figures, and said stripes alternate with narrower stripes formed of spiral or twisted ribbons and a continuous branch of roses and leaves interlacing with said ribbon 20 stripes as shown in the drawing. The border or upper portion of the design is formed of

festoons of ribbons carrying bunches or sprays of roses and leaves and a medallion figure filled with roses and leaves and attached to the festoons by a bow of ribbon. 25 Below the festoons is arranged a horizontal stripe formed of spiral or twisted ribbons and a running branch of roses and leaves interlaced with said ribbons as shown in the drawing. 30

What I claim is—

1. The design for wall paper herein shown and described.
2. In the design for wall paper, the border herein shown and described. 35

Witness my hand this 28th day of July, 1894.

CHARLES BOOZE.
